UNITED STATES PATENT OFFICE.

CHARLES L. KIK, OF LOS ANGELES, CALIFORNIA.

ICELESS REFRIGERATOR.

1,422,364.

Specification of Letters Patent. Patented July 11, 1922.

Application filed May 20, 1920. Serial No. 382,773.

To all whom it may concern:

Be it known that I, CHARLES L. KIK, a citizen of the United States, residing at Los Angeles, in the county of Los Angeles and State of California, have invented new and useful Improvements in Iceless Refrigerators, of which the following is a specification.

This invention relates to iceless refrigerators and has for its object to provide improvements in the construction and details of such devices, and the invention consists of the details and construction an embodiment of which is illustrated in the accompanying drawings and described and claimed herein.

Figure 1 is a perspective of the front of the complete refrigerator.

Fig. 2 is a central transverse vertical section on a plane between the front and back walls.

Fig. 3 is a transverse vertical section on a plane between the side walls.

Fig. 4 is a sectional view showing details of construction adjacent one of the top corners of the refrigerator.

Fig. 5 is a detail horizontal section on line 5-5 of Fig. 4.

Fig. 6 is a perspective of a fragment of the wall structure of the inner chamber.

Fig. 7 is a plan view of the weight member for the bottom of the capillary curtain or wall.

Fig. 8 is a perspective showing the pan having a series of supporting devices extending upwardly above its edge to receive the capillary curtain.

Fig. 9 is a transverse sectional view showing the curtain arranged thereon.

The refrigerator comprises an exterior casing or box of any suitable material, proportion and form of construction, the casing comprising side panel members 2, a back panel member 3 and a preferably hollow front door 4 hinged or otherwise connected at 5-5 of one of the corners of the casing. The side and back panels are provided with large openings or windows as at 6 and the bottom 7 of the casing forms a pan or receiver for such water as may collect in the bottom of the casing, this water being introduced into the bottom pan 7 by reason of the use of water as a cooling agent to maintain a temperature interior of the casing lower than the exterior atmospheric tem-

perature. Such excess or collected water may be drained as required by a drain pipe or valve 8, Fig. 3. The top of the casing is provided preferably with a removable cover 9 that is shown as provided with down-turned flanges 10 making a snug fit around the top edge of the casing structure.

One of the features of my invention consists in means for the form of reticulated or screen panels 11 adapted to be removably mounted on the inner faces of the side and back walls of the casing, the edges of the windows of the casing walls being provided with suitable guide means, as for instance by turning back the material, as metal, to form a channel-like guide way 12 along opposite parallel vertical edges of the window opening 6, as clearly shown in Fig. 5. To determine the position of the removable screen or foraminous panel 11, the edge of 75 which is mounted or formed with a rigid frame 11', the latter has connected to it at suitable points along its top edge upwardly extending hooks 13 designed to be hung over the upper edge of the respective back 80 or side panel member.

Within the exterior casing thus formed there is mounted or arranged an inner chamber consisting of a substantially rectangular wall structure the vertical panels of which 85 are indicated at 14, and these panels are preferably reticulated as for instance by having numerous perforations 15 of desired size throughout the area of the panels thus enabling the free circulation of air into and 90 out of the interior chamber formed by the walls 14. Preferably the front wall of this chamber is left open and is co-extensive with the area of the front door which fits in an inturned flange 4' provided therefor in the 95 front of the casing.

The inner chamber is preferably made of sheet metal perforated as above described and is bent on vertical lines to form the corners at each of which there is provided a 100 downwardly extending lug 16 supporting the inner chamber with its lower edges above the bottom of the pan 7, and the lower horizontal edges of the side and back walls of the inner chamber are shown as turned 105 or bent upwardly at 18 to form little shelves on which rest the bottom 19 of the inner chamber. One or more adjustable intermediate shelves may be arranged at any desired height or heights in the inner chamber 14 110

and the shelf or shelves are hung removably on detachable hangers or hooks 21 having upwardly and outwardly turned ends 22 engaging through the different apertures 15 as 5 may be desired according to the position of the intermediate shelf or shelves 21. The lower ends of these hooks 21 extend inwardly under the shelf 20, as clearly shown in Fig. 2.

- 10 The top of the chamber 14 is open and the top edges of the walls thereof are turned outwardly as at 23 and disposed thereon is a removable water vessel 24 of suitable depth and co-extensive with the plan of the opening of the top of the chamber 14. This pan 24 has outwardly turned flanges 25 resting on the flange 23 at the top of the chamber 14.

For the purpose of securing the cooling effect in the interior of the refrigerator a curtain or capillary wall or wall structure is provided that is suspended in an intermediate position in the space between the outer casing walls and the inner chamber walls, 25 as clearly shown in Figs. 2 and 3, and this capillary wall or curtain comprises a sheet of fibrous or woven material as 26 of suitable length and width and is set in vertical planes passing around the inner chamber except at 30 the front portion thereof where the door 4 extends in across the intervening space.

This curtain 26 is of such length as to have its upper end folded inwardly over the top supporting flange 25 of the vessel and 35 hang well down into the same as at 27 to be well immersed in water that may be supplied thereto as by a faucet 28 connected to a supply pipe 29. The outwardly directed flange 25 of the top of the vessel serves to properly 40 position the vertical panels or wall-like portions of the curtain 26 over the outer edge of which it hangs freely down as shown, and the cloth may be temporarily fastened against dislodgment as by suitable fasteners 45 30 passing through the flanges 25 and 23 at the top of the inner chamber. These fasteners are preferably made of inexpensive material and may, and preferably do, consist of the ordinary well known type of 50 paper fasteners because of their inexpensive character.

In action of the device when water is supplied to the upper vessel 24 from the supply means 28 to a suitable degree the capillary 55 property of the fabric or fibrous wall or curtain 26 causes the water to creep upwardly from the pan 24 and outwardly and downwardly entirely saturating the capillary wall 26, and this wall being extended to the 60 bottom and entering the pan 7 will discharge such excess of water as may be thus drawn from the supply vessel 24 into the pan this being determined by atmospheric conditions.

65 It is desirable to provide for the arrange-

ment of the flexible or pliant capillary wall 26 with facility and to maintain it in a sufficiently taut condition as to take out undesirable folds and prevent it from contacting with the adjacent surfaces of the spaced 70 walls, and for that purpose the lower end of the curtain 26 is weighted. This weight may comprise a U-shaped member 26' shown in plan in Fig. 7 that may be stitched or otherwise suitably connected to the bottom 75 edge of the curtain 26. This weight member or frame 26' is formed to conform to the plan of the space between the inner and outer walls and to hold the curtain in an intermediate position therein and substantially vertically below the edges of the flanges 23-25.

The device thus described may be located as exigency or convenience may determine upon any suitable support and, if desired, it 85 may be suspended within convenient reach by the attachment of appropriate suspended devices to a set of lugs or ears 33 that are provided adjacent the upper end of the casing 2 and which are outwardly deflected as 90 clearly shown in Fig. 1 to provide clearance for the application of the cover 9. These brackets or suspending lugs 33 may be perforated as at 33' for the attachment of wires or other suitable and durable fastening 95 means.

For the purpose of providing for the maximum capillary efficiency of the curtain or wall 26, I prefer to provide for the upper edge of the side walls of the vessel 24 a series 100 of supporting devices preferably having rounded upper surfaces 35 these extending inwardly and outwardly from the vertical plane of the walls of the vessel 24, so that when the capillary cloth 26 is draped over 105 the supporting devices 35 the body portions of the fabric 26 is maintained entirely out of contact with the inside surface of the vessel and with the outside surface of contiguous walls.

These supporting means may be conveniently and inexpensively formed of strips of material of suitable width folded into a loop or bight with the ends riveted or otherwise secured on opposite sides of the vessel wall as 110 at 35'; a series of these supporting devices 35 being placed at suitable intervals along the top edge of the vessel walls.

Various changes may be made without departing from the spirit of my invention as 115 claimed.

I claim:

1. In an iceless refrigerator, an outer casing having openings and guide means for allowing screens to be slidably mounted to 125 cover said openings, said means comprising a portion of the edges of said openings bent inwardly and thence laterally from the same, said inwardly bent portions forming the side of the guide, the lateral portion the back, 130

and the remaining portions of the edges of said openings forming the front of said guides.

2. In an iceless refrigerator, an outer casing having openings, screens mounted to cover said openings, means for detachably supporting said screens to said casing, said means comprising strap hooks fastened to said screens and adapted to engage the top edge of said casing so as to allow said screen to be free at its lower end.

3. In an iceless refrigerator, a sheet metal

wall having an opening, the metal at the sides of the opening being bent upon itself and thence laterally and thence reversely to 15 form guide ways, a framed screen inserted downwardly into the guide ways to cover the opening, and hooks extending upwardly from the screen and over the edge of the wall so as to support the screen. 20

In testimony whereof I have signed my name to this specification.

CHARLES L. KIK.
